(57) **CLAIM**

The ornamental design for a shelf with wide mouth for multiple glide sheets, as shown and described.

DESCRIPTION

FIG. 1 is a top, right, rear perspective view of a first embodiment of a shelf with wide mouth for multiple glide sheets showing the new design;

FIG. 2 is a front view of the invention illustrated in FIG. 1; FIG. 3 is a rear view of the invention illustrated in FIG. 1; FIG. 4 is a left side view of the invention illustrated in FIG. 1;

FIG. 5 is a right side view of the invention illustrated in FIG. 1;

FIG. 6 is a top view of the invention illustrated in FIG. 1; and,

FIG. 7 is a bottom view of the invention illustrated in FIG. 1.

The broken lines in the drawings depict environment, or portions, of the a shelf with wide mouth for multiple glide sheets that form no part of the claimed design.

1 Claim, 7 Drawing Sheets
